(57) **CLAIM**

The ornamental design for an unmanned aerial vehicle, as shown and described.

DESCRIPTION

FIG. 1 is a perspective view of an unmanned aerial vehicle. FIG. 2 is another perspective view of the unmanned aerial vehicle.

FIG. 3 a front view of the unmanned aerial vehicle.

FIG. 4 is a back view of the unmanned aerial vehicle.

FIG. 5 is a left side view of the unmanned aerial vehicle.

FIG. 6 is a right side view of the unmanned aerial vehicle.

FIG. 7 is a top view of the unmanned aerial vehicle; and,

FIG. 8 is a bottom view of the unmanned aerial vehicle.

In the drawings the broken lines depict portions of the unmanned aerial vehicle that form no part of the claimed design.
